(57) **CLAIM**

We claim the ornamental design for a jewelry with fastener, as shown and described.

DESCRIPTION

FIG. 1 is a front elevation view of a jewelry with fastener, showing the jewelry portion removed from the fastener for clarity of disclosure, the rear view being a mirror image thereof;

FIG. 2 is a top plan view thereof;

FIG. 3 is a bottom plan thereof;

FIG. 4 is a front elevation view of a fastener, removed from the jewelry portion for clarity of disclosure, the rear view being a mirror image thereof;

FIG. 5 is a top plan view thereof;

FIG. 6 is a bottom plan thereof;

FIG. 7 is a front elevation view of a jewelry with fastener; and, FIG. 8 is an isometric view thereof.
